ROTARY SOIL CORING APPARATUS
Almond D. Bull, 520 S. 16th St., Chickasha, Okla.
Filed Mar. 19, 1962, Ser. No. 180,604
9 Claims. (Cl. 173—140)

This is a continuation-in-part of my co-pending application Serial No. 675,790 filed July 2, 1957, and entitled Hydraulic Sail Sampler and Penetrometer, now United States Patent 3,026,951, which application was a division of my United States application for Letters Patent Serial No. 373,072 filed August 7, 1953, now United States Patent 2,868,019 which was a continuation-in-part of my United States application for Letters Patent 222,225, filed April 24, 1951, and now United States Patent 2,701,121.

This invention relates generally to improvements in apparatus for obtaining soil samples, and more particularly, to such an apparatus wherein the coring tube is both driven and rotated into the earth to obtain a core sample.

As it is well known in the art, it is common practice to force a coring or sampling tube into the earth, such that a core of soil is received in the tube and can be studied or analyzed upon withdrawal of the tube from the earth. An apparatus which has been proven commercially successful is disclosed in my U.S. Patent No. 2,868,019 issued January 13, 1959. This apparatus utilizes a pair of driving chains mounted on a mast structure with a coring tube supported by the chains through the medium of a driving head. The chains are moved lengthwise by a hydraulic drive system for forcing the coring tube downwardly in the earth and, alternately, for raising the coring tube for inspection of the core contained in the tube. As indicated, the apparatus has been highly useful. However, such apparatus requires an excessive amount of power when used to take samples in hard soils, such as shales and sandstones, or to take samples in compacted, high density soils in a roadway, since the cutting action of the coring tube is obtained solely by a downward movement of the tube into the earth.

In one aspect, the present invention may be considered an improvement on the apparatus disclosed in the above-mentioned patent. Basically, the present invention contemplates the use of a rotary drive system in combination with a vertical drive system for a soil coring tube, such that the coring tube is not only forced downwardly into the earth but is also rotated to obtain a cutting action and minimize the force required to drive the tube into the earth. More specifically, the present invention contemplates the combination of a vertically extending mast which may be easily mounted on a transporting vehicle; at least one chain mounted on the mast; a drive system for moving the chain lengthwise along the mast; a driving head carried by the chain for vertical movement along the mast upon movement of the chain; a rotary head carried by the driving head for vertical movement with the driving head; means for turning the rotary head about a vertical axis during vertical movement of the rotary head; a coring tube; a drill stem connecting the rotary head to the coring tube for moving the coring tube vertically and rotatably; and a cutter on the lower end of the coring tube for cutting a core in the earth which is received in the coring tube as the coring tube is moved downwardly and rotated. The drive system for the rotary head is preferably hydraulic and utilizes a square shaft or kelly between the hydraulic drive and the rotary head to facilitate the vertical movement of the rotary head during rotation. The drill stem is preferably a series of joints which can be easily disconnected, without the use of expensive or complicated tools, for regulating the depth of penetration of the coring tube.

2

An important object of this invention is to obtain soil samples anywhere from shallow to relatively deep depths in all types of soils.

Another object of this invention is to provide a soil sampling apparatus wherein the coring tube may be driven through asphaltic or concrete road beds and the like, as well as into hard soils such as consolidated shales or soils containing rock.

Another object of this invention is to provide a portable soil sampling apparatus wherein the coring tube is forced into the earth or other medium while simultaneously being rotated.

Another object of this invention is to obtain a soil sample at substantially any desired depth in a minimum of time and with a minimum of manual labor.

A further object of this invention is to provide a vertically movable and rotary soil sampling apparatus which may utilize any desired power, such as hydraulic or electric, or a gasoline motor.

20 A still further object of this invention is to provide a simply constructed soil sampling apparatus which may be economically manufactured and which will have a long service life.

Other objects and advantages of the invention will be 25 evident from the following detailed description when read in conjunction with the accompanying drawings which illustrate the invention.

In the drawings:

FIGURE 1 is a side elevational view of a sampling apparatus constructed in accordance with this invention.

30 FIGURE 2 is another elevational view of the apparatus taken from the right-hand side shown in FIGURE 1.

FIGURE 3 is a sectional view taken along lines 3—3 of FIGURE 1.

45 FIGURE 7 is a sectional view taken along lines 7—7 of FIGURE 6.

FIGURE 8 is a sectional view taken along lines 8—8 of FIGURE 7.

50 FIGURE 9 is an elevational view of a modified drive system for the rotary head.

Referring to the drawings in detail, and particularly FIGURES 1, 2 and 3, reference character 12 generally designates a sampling apparatus utilizing a mast 14 supported in a vertical position in any desired manner. For 55 example, the mast 14 may be secured on a base plate or foundation 15 by use of angle iron braces 16 suitably bolted to the base plate 15 and the sides of the mast. Additional bracing 18 may be provided between a bracket 20 at the upper end of the mast and another bracket 22 along the length of the mast, if desired. An additional bracket 24 is secured to the lower end of the mast for purposes to be described. As shown in the drawings, the mast 14 is preferably in the form of an I-beam and each of the brackets 20, 22 and 24 is in the 60 form of plates suitably bolted to the sides of the mast.

Sprockets 26 and 28 are journaled in the upper and lower brackets 20 and 24 to receive a pair of drive chains 30 extending along the length of the mast 14. The upper portion of each drive chain 30 is extended downwardly 65 along the back 31 of the mast 14 underneath a sprocket 32, and then upwardly for connection with the upper bracket 20 by suitable bolts 34. The lower portion of

each drive chain is extended upwardly along the back 31 of the mast 14 over a sprocket 36 and then downwardly into connection with the intermediate bracket 22 by suitable anchor bolts 38. The sprockets 32 and 36 are mounted on a clevis 40 for movement upwardly and downwardly in unison to move the drive chains 30 vertically along the front 42 of the mast 14. It will be apparent that when the clevis 40 is moved upwardly, those portions of the drive chains 30 extending along the front 42 of the mast 14 will move downwardly, and when the clevis 40 is moved downwardly the same portions of the drive chains will be moved upwardly.

The clevis 40 is moved by a suitable double-acting hydraulic ram 44 having its piston rod 46 connected to the lower end of the clevis. The action of the ram 44 is controlled by a suitable hydraulic system 48 having a hydraulic pump 50 and four-way valve 52. The details of construction of the hydraulic system 48 form no part of this invention and it is not believed necessary to describe the system in detail herein. It may be noted, however, that the pump 50 may be easily driven from the power take-off of a motor vehicle when the apparatus is mounted on the vehicle to minimize the cost of the installation. On the other hand, the drive chains 30 may be driven by any suitable power source, such as electrical or pneumatic if desired.

As shown most clearly in FIGURE 3, the portions of the chains 30 extending along the front 42 of the mast 14 are guided by suitable channel members 54 welded between the opposite webs of the I-beam mast. A mounting plate 56 is firmly secured to the chains 30 at the front 42 of the mast by welding, such that the plate 56 will be moved vertically upon lengthwise movement of the chains 30. As illustrated in FIGURES 1 and 2, the mounting plate 56 is secured to the chains 30 near the upper end of mast 14 when the clevis 40 is in its lowermost position to provide the maximum vertical travel of the mounting plate. It may also be noted in FIGURE 3 that suitable angle iron guides 59 are secured to the opposite sides of the mast 14 in positions to guide the mounting plate 56 and prevent movement of the mounting plate away from the mast. It is preferred that the angle irons 59 extend over substantially the entire length of the mast 14 for controlling the complete travel of the mounting plate.

A driving head 60 is rigidly secured to the mounting plate 56, as by welding. The driving head 60 is preferably constructed in the manner disclosed in my U.S. Patent 2,868,019, with a coupling structure 62 (FIGURE 4) on the lower end thereof for connection with a coring tube in the event it is desired to use the apparatus with only a vertical movement of coring tube for a coring operation, such as may be desirable in relatively soft soils. Also, a T-shaped flange 63 is preferably secured (FIGURE 3A) on the lower end portion of the head 60 to extend under the angle irons 59 and help retain the head 60 vertical. However, the flange 63 can be moved from side-to-side under the angle irons 59 a short distance to slightly pivot the head 60 if necessary during operation, such as when hitting a rock.

In accordance with the present invention, a rotary head, generally designated by reference character 64, is carried by the driving head 60, preferably on the side of the driving head opposite the mast 14. As shown in FIGURE 4, the rotary head comprises a vertical shaft 66 extending through a bearing housing 68 and having a sprocket 70 on the upper end thereof. The sprocket 70 is rotated in a manner to be described for rotating the shaft 66 about a vertical axis. A double tapered bearing race 72 is suitably secured around the shaft 66 within the housing 68 to cooperate with tapered or Timken bearings 74. The bearings 74 are positioned between the inner race 72 and outer races 76 suitably secured in the housing 68 to support the shaft 66 in a fixed vertical position in the housing 68 and accommodate both radial and axial thrusts im-

posed on the shaft. A guide tube 78 is secured to the housing 68 around the shaft 66 and extends downwardly around the shaft. Suitable sealing or packing rings 80 are positioned in the tube 78 around the shaft 66 to prevent the leakage of lubricant out of the lower end of the tube. It is preferred that the housing 68 be filled with a suitable lubricant to facilitate the operation of the bearings 74. The bearing housing 68 and the tube 78 are rigidly secured to the driving head 60, as by welding, for vertical movement of the rotary head 64 with the driving head.

The coring tube 82 (FIGURES 1 and 2) is connected to the rotary head 64 by a drill stem 84 shown in detail in FIGURE 4. Basically, the drill stem 84 comprises a plurality of joints of elongated elements interconnected in tandem relation to position the coring tube 82 any desired distance below the rotary head 64 while moving the coring tube vertically and simultaneously rotating the coring tube. In a preferred form, the drill stem 84 comprises an upper joint 86 in the form of a solid shaft which is threadedly connected at its upper end 88 to the lower end 90 of the rotary head shaft 66. An open-ended box 92 is secured on the lower end of the joint 86 in any suitable manner, as by welding. The box 92 cooperates with a mating open-ended box 94 suitably secured on the upper end of the next lower joint 96.

As shown in FIGURES 4 and 5, the boxes 92 and 95 are square in cross section, and the box 94 is of a size to be telescoped into the box 92. Thus, rotation of the upper joints 86 will be translated through the boxes 92 and 94 to the next lower joint 96. Cooperating or mating apertures 98 and 100 are formed in corresponding sides of the boxes 92 and 94 to receive a tapered latching pin 102 for retaining the boxes in their telescoped positions. The pin 102 is secured on the free end 104 of a U-shaped spring 106 secured inside of the smaller box 94 by a fastener 107. The spring 106 is preferably sufficiently resilient that the pin 102 may be forced inwardly through the mating apertures 98 and 100 for withdrawal of the box 94 from the box 92 manually without the use of any special tools. It will be apparent, however, that when the pin 102 is positioned in the bores 98 and 100, the box 94 cannot be removed from the box 92 and the joints 86 and 96 will be adequately interconnected. It will also be noted that since the upper edge 102a of the pin 102 is tapered, the pin will move inwardly upon insertion of the box 94 in the box 92, and then outwardly through the aperture 100 as the boxes are fully telescoped.

The joint 96 may take any desired form, such as a joint of pipe which has the required strength and rigidity. Any desired number of joints 96 may be used and the adjacent joints are interconnected by boxes 94 and 92 in the same manner as shown in FIGURE 4 to provide easy removal and installation of the joints. The lower joint of the drill stem 84 is suitably secured to the upper end of the coring tube 82 as illustrated in FIGURES 1 and 2. The coring tubing 82 may take any desired form, such as disclosed in the above-mentioned patent. A suitable annular cutter 108 is secured on the lower end of the coring tube to provide a cutting action upon rotation of the cutter. The cutter 108 may take any desired form, such as a short joint of tubing or pipe having teeth in the lower end thereof as illustrated in FIGURES 1 and 2. It will be understood that the coring tube 82 and cutter 108 may be replaced by a soils auger to obtain disturbed soil samples if desired.

The sprocket 70 of the rotary head 64 is driven by an endless chain 110 extending around the sprocket 70 and another sprocket 112 as illustrated in FIGURE 6. The sprocket 112 is drivingly connected and slidably secured on a shaft or kelly 114 having a square cross section. The sprocket 112 is retained at the same level as the sprocket 70 of the rotary head 64 by a bearing assembly 116 on the shaft 114 and a yoke 118 extending from the rotary head 64 to the bearing. As shown most clearly in FIG-

URE 8, the bearing 116 comprises an inner race 120 having a square bore therethrough for cooperation with the square shaft 114 and being connected at its upper end to the sprocket 112, as by welding. An outer race 122 is journaled on the inner race 120 and held in a fixed position longitudinally of the inner race 120 by a flange 124 and a plate 126 at the upper and lower faces of the outer bearing race. It will thus be apparent that the inner bearing race 120 and the sprocket 112 will turn with the square shaft 114, but they may be moved vertically on the shaft 114. The outer bearing race 122 may or may not turn since it is journaled on the inner bearing race. A groove 128 is provided around the outer bearing race 122 to receive the outer end portion 130 of the yoke 118. As shown in FIGURE 7, a groove 132 is provided in the outer end 130 of the yoke 118 to fit around the outer bearing race 122 in the groove 128. The groove 132 is somewhat less than a semicircle in order to facilitate the connection of the yoke 118 to the bearing 116. The opposite end of the yoke 118 is rigidly secured to the housing of the rotating head 64, as by welding.

As shown in FIGURE 2, the upper end 134 of the square shaft 114 is extended above the sprocket 112 and is journaled in a suitable bearing 136 secured to the respective side of the mast 14. The lower end of the shaft 114 is journaled in a base plate 138 suitably secured to and extending outwardly from the respective side of the mast 14. Thus, the square shaft is retained parallel with the mast 14 and is supported to rotate about its longitudinal axis. The lower end of the shaft 114 is connected to a suitable hydraulic motor 140 through a gear arrangement 142 for rotating the square shaft. Both the hydraulic motor 140 and gear box 142 are suitably supported from the base plate 138. It may also be noted that the base plate 138 is supported only slightly above the base plate 15 of the mast 14 in order that the driving head and the rotating head may be moved downwardly the maximum extent for a coring operation.

Operation

Prior to taking a soil sample, the hydraulic system 48 is operated to actuate the ram 44 and lower the clevis 40 to raise the driving head 60 and rotary head 64 to the upper end of the mast 14. The coring tube 82, with the cutter 108 on the lower end thereof, is then secured to the rotating head 64 by the drill stem 84. A sufficient number of joints are used in the drill stem 84 to position the cutter 108 below the mast 14, but above the surface of the earth.

The hydraulic motor 140 is then placed in operation to rotate the square shaft 114 through the gear box 142. The shaft 114 drives the shaft 66 of the rotary head 64 through the medium of the sprockets 112 and 70 and chain 110, to in turn rotate the cutter 108 through the drill stem 84 and coring tube 82. The hydraulic system 48 is then operated to actuate the ram 44 and force the clevis 40 upwardly. Upward movement of the clevis 40 drives the drive head 60 and rotary head 64 downwardly along the mast 14 through the medium of the chains 30. The simultaneous downward force and rotary force imposed on the cutter 108 provides an efficient cutting action to facilitate the penetration by the cutter 108 and the coring tube 82. As the cutter 108 moves downwardly through the earth, a core is formed and enters the coring tube 82.

When the coring tube 82 is filled with a core, the coring tube is retracted by operation of the hydraulic system 48 until the coring tube is above the surface of the earth. The core in the tube 82 is then removed and the coring operation repeated by further downward movement of the coring tube 82 and cutter 108. This operation is repeated until a core sample is taken at the desired depth.

In the event the drill stem 84 as originally assembled is not sufficiently long to obtain the desired penetration, the drill stem may be easily lengthened by insertion of

additional joints 96. Normally, one of the box connections shown in FIGURE 4 along the length of the drill stem 84 is parted while the coring tube 82 is inserted in the ground. The rotary tube 64 is then raised sufficiently for the insertion of an additional joint 96. When this new joint is inserted in the drill stem 84, the rotary head 64 is again driven downwardly for a lower core sampling operation. The downward movement of the rotary head 64 may be continued until the bearing 116 is in contact with or substantially in contact with the base plate 138. In this connection, it will be noted that the sprocket 112 is moved downwardly along the square shaft 114 by use of the yoke 118 and bearing 116 to retain the sprocket 112 at the same level as the sprocket 70 on the rotary head 64. Thus, the drive chain 110 encircling the sprockets 70 and 112 will be retained level and in operating position in all vertical positions of the rotary head 64.

The apparatus 12 is particularly suited for use on a motor vehicle since it can be easily mounted on the bed of a vehicle, the draw bar of a tractor, or on an auxiliary trailer, and not be extended unduly high from the vehicle. Also it will be noted that the hydraulic system 48 and the hydraulic motor 140 are both positioned in proximity with the bed of the vehicle to facilitate the connection of the hydraulic system and motor to power equipment in existence on a motor vehicle.

In the event of any malfunction of the drive system for the rotary head 64, the coring tube 82 and cutter 108 may be simply driven in the ground with no rotation. This same type of operation may also be obtained by simply securing the coring tube 82 to the connection 62 of the drive head 60. Such operations are sometimes desirable in obtaining samples of extremely loose or wet soils which would be disturbed by a rotary action of the cutter 108 and coring tube 82.

A modified embodiment of the invention is partially illustrated in FIGURE 9. In this embodiment, the mast 14 (except for the structure at the upper end thereof), the driving head 60, the driving system for raising and lowering the driving head 60, and the rotary head 64 remain the same as shown in the previous figures. The change in this embodiment shown in FIGURE 9 is solely with respect to the system used for rotating the shaft 66 of the rotary head 64.

As shown in FIGURE 9, a square shaft or kelly 200 is connected directly to the upper end of the rotary head shaft 66 by a suitable coupling 202 and extends vertically upward from rotary head 64. The square shaft 200 is supported in such vertical position by a pair of bearing assemblies 204 supported by suitable brackets from plates 205 extending upwardly from both sides of the mast 14. Each bearing assembly 204 includes an inner race 206 having a square bore therethrough to slidably receive the square shaft 200, and an outer race 208 in which the inner race 206 is journaled. Thus, the bearings 204 will retain the shaft 200 vertical, yet the shaft 200 may rotate and move vertically through the bearings 204.

A sprocket 210 is slidably secured on the square shaft 200 on top of the lower bearing assembly 204 to turn with the shaft 200 and yet allow vertical movement of the shaft 200 therethrough. An endless chain 212 extends around the sprocket 210 and another sprocket 214 driven by a suitable hydraulic motor 216. The motor 216 may be supported by one or more arms 218 extending rearwardly from the plates 205, as by brackets 220. It will be understood that the hydraulic motor 216 is secured between the arms 218 in order for the chain 212 to encircle both of the sprockets 210 and 214 and extend between the plates 205. The hydraulic motor 216 is suitably connected to a hydraulic system (not shown).

In operation of the embodiment shown in FIGURE 9, the hydraulic motor 216 is placed in operation to rotate the square shaft 200 through the medium of the sprockets

210 and 214 and endless chain 212. As the driving head 60 and rotary head 64 are moved downwardly in a sampling operation, the shaft 209 moves downwardly through the bearing assemblies 204 and the sprocket 210 while retaining the driving connection of the shaft to the hydraulic motor 216. Thus, the square shaft 200 must have a length at least as great as the stroke of the driving head 60 and rotary head 64.

From the foregoing, it will be apparent that the present invention provides an apparatus by which core samples of all types of soils may be obtained. The coring tube may be driven through asphalt or concrete as may be overlying or forming a road and obtain a sample of soil underneath the road. The coring tube is both rotated and forced downwardly to obtain a cutting action with a minimum energy requirement. Alternatively, the coring tube may be simply driven downwardly to obtain a sample in those soils which would be disturbed by a rotary motion of the coring tube. It will further be apparent that the present apparatus is simple in construction, may be economically manufactured and will have a long service life.

Changes may be made in the combination and arrangement of parts or elements as heretofore set forth in the specification and shown in the drawings, it being understood that changes may be made within the spirit and scope of the invention as defined in the following claims.

What is claimed is:

1. Apparatus for taking a core sample of the earth comprising:

a generally vertically extending mast;
at least one chain mounted on the mast;
drive means on the mast for moving the chain lengthwise along the mast;
a driving head carried by said chain for vertical movement along the mast upon movement of the chain, said driving head including an elongated vertically extending member having a coring tube connection on the lower end thereof;

a rotary head carried by the driving head for vertical movement with the driving head and positioned above the lower end of the driving head whereby said coring tube may be connected to the rotary head, and alternately, to the driving head, depending upon the soil condition encountered;

means for turning the rotary head about a vertical axis during vertical movement of the rotary head; a coring tube having an upper and a lower end; a drill stem connecting the rotary head to the upper end of the coring tube for moving the coring tube in the same motions as the rotary head; and a cutter on the lower end of the coring tube for cutting a core in the earth which is received in the coring tube as the coring tube is moved downwardly.

2. Apparatus as defined in claim 1 wherein said rotary head comprises:

a vertically extending shaft;
a sprocket on the upper end of the shaft connected to said means for turning the rotary head;
a bearing race secured around the shaft; and
bearing means carried by the driving head cooperating with said race for transmitting the vertical movement of the driving head to the rotary head during rotation of said shaft.

3. Apparatus as defined in claim 1 wherein said means for turning the rotary head about a vertical axis includes: a kelly rotatably supported parallel with the mast; means for turning the kelly; and means connecting the kelly to the rotary head.

4. Apparatus as defined in claim 3 wherein said means connecting the kelly to the rotary head comprises:

a first sprocket slidably secured on the kelly for vertical movement on the kelly for rotating with the kelly; a second sprocket on the rotary head;

an endless chain extending around said first and second sprockets; and means retaining said first and second sprockets level with one another during vertical movement of the rotary head.

5. Apparatus for taking a core sample of the earth comprising:

a vertically extending mast;
at least one chain mounted on the mast;
drive means on the mast for moving the chain lengthwise along the mast;
a driving head carried by the chain for vertical movement along the mast upon movement of the chain;
a rotary head carried by the driving head for vertical movement with the driving head;
a kelly rotatably supported parallel with the mast;
means for turning the kelly;
a first sprocket slidably secured on the kelly for vertical movement on the kelly for rotating with the kelly;

a second sprocket on the rotary head;
an endless chain extending around said first and second sprockets;

a bearing on the kelly having an inner race slidably secured on the kelly and an outer race rotatable on the inner race, said inner race being secured to said first sprocket for vertical movement with said sprocket upon vertical movement of the bearing;

a yoke connecting the outer race of said bearing to said driving head for moving said bearing and said first sprocket upon vertical movement of the driving and rotary heads;

a coring tube having an upper end and a lower end; a drill stem connecting the rotary head to the upper end of the coring tube while moving the coring tube in the same motions as the rotary head; and a cutter on the lower end of the coring tube for cutting a core in the earth which is received in the coring tube as the coring tube is moved downwardly.

6. Apparatus for taking a core sample of the earth comprising:

a vertically extending mast;
at least one chain mounted on the mast;
drive means on the mast for moving the chain lengthwise along the mast;

a driving head carried by the chain for vertical movement along the mast upon movement of the chain;
a rotary head carried by the driving head for vertical movement with the driving head;

a kelly rotatably supported parallel with the mast and positioned above, and in alignment with the rotary head;

a pair of bearings secured to the mast and slidably supporting the kelly for vertical movement of the kelly; a first sprocket secured on the kelly and slidably along the kelly;

a hydraulic motor mounted on the mast;
a second sprocket driven by the hydraulic motor;
an endless chain around the first and second sprockets; means connecting the kelly to the rotary head;

a coring tube having an upper end and a lower end; a drill stem connecting the rotary head to the upper end of the coring tube for moving the coring tube in the same motions as the rotary head; and,

a cutter on the lower end of the coring tube for cutting a core in the earth which is received in the coring tube as the coring tube is moved downwardly.

7. Apparatus for taking a core sample of the earth comprising:

a vertically extending mast;
at least one chain mounted on the mast;
drive means on the mast for moving the chain lengthwise along the mast;

a driving head carried by the chain for vertical movement along the mast upon movement of the chain;

a rotary head carried by the driving head for vertical movement with the driving head; means for turning the rotary head about a vertical axis during vertical movement of the rotary head; a coring tube having an upper end and a lower end; a drill stem connecting the rotary head to the upper end of the coring tube for moving the coring tube in the same motions as the rotary head, said drill stem comprising:

10 a plurality of elongated joints; and a quick opening coupling between adjacent joints comprising:

a first open-ended box on the lower end of the upper joint of the adjacent joints;

15 a second open-ended box on the upper end of the lower joint of the adjacent joints, said second box being telescopically extended into the first box, said boxes having mating apertures in corresponding sides thereof when the second box is positioned 20 in the first box;

a latching pin supported in the second box in a position to extend through said mating apertures for coupling said boxes together; and

25 a spring in the second box biasing said pin outwardly through said apertures whereby said boxes are uncoupled by forcing said pin inwardly into the second box; and

a cutter on the lower end of the coring tube for cutting 30 a core in the earth which is received in the coring tube as the coring tube is moved downwardly and rotated.

8. Apparatus as defined in claim 7 and wherein said spring is U-shaped and is secured at one free end thereof in the second box; and said pin is secured on the other free end of said spring.

9. In an apparatus for taking a core sample of the earth, the combination of:
a vertically extending mast;
at least one chain extending along the length of the mast,
drive means on the mast for moving the chain lengthwise along the mast;
an elongated driving head for a coring tube having an upper end and a lower end;
means securing the driving head to the chain near the upper end of the driving head;
vertical guides secured to the mast at opposite sides of the chain providing flanges spaced from the mast and extending toward each other, and
a T-shaped flange secured to the driving head near the lower end thereof extending between each of said flanges and the mast for retaining the driving head substantially vertical, said T-shaped flange being sized to slide from side-to-side between said flanges and the mast.
